UNITED STATES PATENT OFFICE.

OSCAR B. LINQUEST, OF JAMESTOWN, NEW YORK, ASSIGNOR OF ONE-HALF TO
ARCHIBALD F. RUSSELL, OF LAKEWOOD, NEW YORK.

ELECTRIC HEATER FOR OIL-WELLS.

957,785.

Specification of Letters Patent. Patented May 10, 1910.

Application filed June 29, 1909. Serial No. 505,021.

To all whom it may concern:

Be it known that I, OSCAR B. LINQUEST, a citizen of the United States, and a resident of Jamestown, county of Chautauqua, State 5 of New York, have invented certain new and useful Improvements in Electric Heaters for Oil-WellS, of which the following is a full, clear, and exact description.

My invention relates to means for heating 10 oil wells for the purpose of cleaning accumulated deposits of paraffin from the interior of such wells and more particularly my invention relates to an electric heater for the purpose just stated.

15 It is well known that after oil wells have been flowing for some length of time the crevices in the oil bearing strata of rocks become more or less clogged with paraffin deposits which interfere with the flow of the 20 wells.

25 The general object of my invention is to provide a means for removing the paraffin when so deposited and thus to provide a practicable and efficient means for increasing the flow of the well.

30 Various methods have been suggested for heating wells for the purposes described but these devices have been lacking in efficiency of operation and cheapness of manufacture 35 and use.

35 My invention provides an efficient and cheap means for effectively heating any oil well so as to remove the paraffin deposits in it; moreover it is simple and cheap in construction and likewise cheap in operation.

The many advantages resulting from the use of my invention will be clear to those skilled in the art from the accompanying drawings and the following description.

40 Referring to the drawings: Figure 1 is a sectional view of the casing of my device and an elevation of the heating element. Fig. 2 is a section taken on the line $w-w$ of Fig. 1. Fig. 3 is a section taken on the line 45 $y-y$ of Fig. 1. Fig. 4 is a section taken on the line $z-z$ of Fig. 1. Fig. 5 is a section taken on the line $z'-z'$ of Fig. 1.

50 It will be understood that my device is to be lowered in any suitable way into any desired part of the well. It is in general provided with a tubular casing 1 which is designed to pass within the casing or other confines of the well. The casing 1 is open at its top and bottom ends so that oil con-

tained in the well may pass within the said 55 casing 1.

Suitably secured to the lower end of the casing 1 is a strap iron 2. A similar strap iron 3 is secured to the upper end of the casing 1. Suitable iron rods 4 pass through 60 the strap irons 2 and 3 and are secured by means of nuts 5 or in any other suitable way. On these rods are mounted grooved porcelain tubes 6. The porcelain tubes 6 extend substantially all of the distance between the 65 strap irons 2 and 3 and preferably they are made up of short sections but I do not wish to limit myself to this particular arrangement. The advantage of this construction is that it gives flexibility to the tubes. The 70 tube sections are suitably grooved at predetermined spaces from each other for the purpose of receiving a resistance wire for conducting the electric current.

75 On the iron rods 4 I preferably mount three nuts 5, 7 and 8; the nuts 8 acting to hold the grooved porcelain tubes in place; between the nuts 7 and the nuts 8 I place rings 9 and the nuts 7 and 5 are placed on either side of the strap irons 2 and 3. 80 Through the ring 9 are passed rods 10. Upon the rods 10 I mount grooved porcelain tubes of the same character and in the same way as the grooved porcelain tubes are mounted on the rods 4. Although I have 85 shown in my drawings four iron rods on which these grooved porcelain tubes are mounted it will be understood that I do not wish to confine myself to the exact number and arrangement of rods and tubes as herein 90 shown but it is obvious that two or more tubes could be arranged for accomplishing the purposes I accomplish by the device herein described.

95 At suitable distances along the length of the tubes 4 and 10 I preferably place spacers 11 which are notched on their edges so as to fit around the tubes 4 and 10. The function of these spacers is to keep the said tubes in their proper relation to each other. Preferably these spacers also are perforated at 13 so as to allow the electric leading wire to pass through them. Obviously the number of spacers to be used will depend on the length of the heater element. 100 105

At the upper end of the casing I arrange a terminal block 14 which is secured in any suitable way to the bail 15 of the casing.

This bail 15 is secured by rivets or otherwise at 16 to the side walls of the casing. Passing through the terminal block are electrical connectors 17 which are secured in place 5 in said block by means of set screws 18. Lead wires 19 and 20 pass into the connectors 17 and are held in place therein by means of the set screws 18. The wire 20 leads from one of the connectors 17 through 10 a porcelain bushing 21. This bushing 21 passes through the top strap 3 and is held in place by it. The lead wire 20 then passes in the space between the porcelain tubes 4 and 10 and through one or more of the 15 spacers 11 to the bottom of the heating element where it is suitably connected to the resistance wire 22 which is wound on the outside of the series of grooved porcelain tubes. The insulated lead wire 19 is suitably 20 secured to the upper or opposite end of the resistance wire 22 at one end and then passes through a porcelain bushing 23 which bushing is held in place in the strap 3 similarly to the bushing 21. The other end of the 25 lead wire 19 then passes into the connector 17 and is there held in place by means of the set screws 18 in a manner similar to the means described for holding in place the end of the wire 20. The electric connections 30 24 and 25 for the conductors 19 and 20 lead from the electric connectors 17 in which they are secured in the terminal block 14 by means of the set screws 18. These connecting wires may lead to a generator or any 35 other suitable source of energy.

Having thus described the several parts of my invention I will now describe its method of operation. The generated current is turned on to the wires leading from the 40 source of energy and it then passes through the following circuit: wire 24, connector 17, lead wire 20, resistance winding 22, lead wire 19, connector 17, wire 25, back to the source of energy. This current passing, 45 through the heating element composed of the resistance wire 22 wound about the grooved porcelain tubes acts to produce an amount of heat which is proportional to the resistance of the resistance wires and 50 the amount of current passing through the circuit. The heat thus generated acts upon the oil which is in immediate contact with the heating element. This generated heat is sufficient to raise the temperature of the oil 55 enough so that the paraffin deposits anywhere in the well near the heating element will be affected so that they will become soft and be dissolved in the oil. When the paraffin has thus been broken down the 60 oil is bailed out of the well and thus the crevices are cleared and the clogged portion of the well allows a greater flow of oil than was previously possible.

It will be evident from the foregoing description that my invention can be ver-

cheaply and efficiently operated and that it is capable of some variations and modifications which would be governed by varying conditions under which it might be used. I do not, therefore, wish to be limited to the 70 exact construction herein shown and described.

The gist of my invention resides in the fact that I have provided an electrical means of heating an oil well by placing my heater 75 in direct contact with the oil and thus raising the temperature of the oil to a degree sufficient to dissolve paraffin found in the crevices of the well. With this in mind, it will be evident that some departures 80 from the specific construction herein shown and described might be made without departing from the spirit of my invention.

Comparing my invention with those devices which are used for heating oil wells 85 where the heating element is contained within a water-tight or an air-tight case it will be evident that the length of life of my heating element will be much greater than that of the heating element contained in 90 such tight cases. This is so because of the fact that the wires contained in the tight cases must be sufficiently heated so that the casing as well as the oil will be heated, while in my form of heating device, the oil being 95 in direct contact with the wires, the wires are thus kept partially cooled by the oil and the heat is directly taken up by the oil so that the resistance wire in my device need not be as large as is necessary in another 100 device of the inclosed type of the same heating capacity.

Having thus described my invention, what I claim is:

1. An electric heater for oil wells comprising two or more insulating tubes, means for spacing these tubes apart from each other, a resistance wire wound around said tubes, means for conducting a current from any suitable source of energy through said 110 resistance wire, and means for lowering and raising said tubes and wires in any desired position in an oil well.

2. An electric heater for oil wells comprising grooved porcelain tubes, means for spacing said tubes apart from each other, a resistance wire surrounding said tubes, a tubular casing open at the top and bottom surrounding said tubes, a bail for raising and lowering said tubes and casing into and 115 out of an oil well, and means for conducting a current from some suitable electric source of energy through said resistance wire.

3. An electric heater for oil wells comprising grooved porcelain tubes, means for spacing said tubes apart from each other, a resistance wire surrounding said tubes, a tubular casing open at the top and bottom surrounding said tubes, a bail for raising and lowering said tubes and casing into and 125 130

out of an oil well, a terminal block secured to said bail, means for connecting wires from any suitable source of electric energy with said resistance wire.

- 5 4. An electric heater for oil wells comprising grooved porcelain tubes, a casing open at top and bottom, means for securing said tubes in place in said casing, a resistance wire surrounding said tubes, a bail secured to said casing, electric connectors secured in said bail, insulated wire leads leading from said connectors to the terminals of said resistance wire, means for securing the ends of said wire leads in said connectors and means for securing wires from any suitable source of energy in said connectors.
- 10 5. An electric heater for oil wells com-

prising grooved porcelain tubes, means for spacing said tubes apart from each other, a resistance wire surrounding said tubes, 20 means for connecting said resistance wire with a suitable source of electric energy, and means for raising and lowering said elements into and out of an oil well whereby the said elements are brought into direct 25 contact with the oil of the well and thus heat the same.

In testimony whereof I have hereunto set my hand in the presence of two witnesses.

OSCAR B. LINQUEST.
